UNITED STATES PATENT OFFICE.

JASON C. STEARNS, OF WORCESTER, MASSACHUSETTS.

SIDE CONNECTION FOR ELECTRICAL CABLES.

1,179,970.

Specification of Letters Patent. Patented Apr. 18, 1916.

Application filed July 22, 1915. Serial No. 41,417.

To all whom it may concern:

Be it known that I, JASON C. STEARNS, a citizen of the United States, residing at Worcester, in the county of Worcester and State of Massachusetts, have invented a new and useful Side Connection for Electrical Cables, of which the following is a specification.

This invention relates to a connector for electrical cables and also insulated wires, and while capable of general use where it is desired to take off a side connection, it is especially adapted for use on the electric lamps of automobiles.

15 The principal objects of the invention are to provide a simple and compact connector adapted to serve as a plug for insertion in a socket having bayonet slots and to so arrange it that it will be formed of a single 20 block of insulating material; to provide it with simple and convenient means whereby the ends of the wires or cable are held against the conductors which pass through the plug, and the armor or insulation is 25 securely held in sockets in the insulator so that there is no danger of their becoming loose or getting crossed in practice; to provide a construction whereby the means for holding the armor or insulation also constitutes a handle by which the plug can be 30 manipulated; and to provide for securing the ends of the wires or cables in position in such a way that there is no danger of short-circuiting the same by constant vibration or 35 when applying a screw-driver or other tool to fasten or loosen them.

Reference is to be had to the accompaniments in which,

40 Figure 1 is a side elevation of a preferred embodiment of the invention showing it in position on a socket and with an armored cable applied thereto; Fig. 2 is an end view of the same; Fig. 3 is a sectional view on the line 3—3 of Fig. 2, and Fig. 4 is a view 45 similar to Fig. 3, showing a modification.

The invention is shown in a simple form in which it comprises a plug 10 of hard rubber of a general cylindrical form having a flat end surface and provided with radial 50 pins 11 for entering the bayonet slots and a helical socket 12. This plug is preferably made of a single molded body of hard rubber. In addition to the cylindrical plug portion 10, it has an enlarged portion 13 at the other end having a knurled surface surrounding it and preferably of substantially

cylindrical form concentric with the plug 10. It also has a radial flat portion 14 having a material thickness and extending from the enlarged portion so that it constitutes a 60 handle by which the whole device can be manipulated. These parts, except the pins 11, are formed of a single body of hard rubber, all integrally connected together in the molding operation.

65 Extending longitudinally, almost through the entire insulator, are two conductors 16 having flat ends flush with the flat end surface of the plug 10 and provided at their other ends, which are within the enlarged portion of the insulator, with longitudinal central screw-threaded openings 17 for receiving binding-screws 18. The whole rubber member is counter-bored at this point to receive the heads of the screws so that in 70 manipulating them with a screw-driver, there will be no danger of touching both at the same time and short-circuiting the device. Each of these conductors is provided with a radial passage 19 through one wall 75 communicating with the screw-threaded opening, and the projection 14 is provided with two passages 20 in alignment thereto but enlarged. The purpose of these 80 passages is to receive the end of a cable 21 in the passage in the conductor, and the armor 22 thereof in the passage in the insulator. The binding screws are then screwed down on the end of the cable. If a wire is used 85 which has insulation thereon a similar 90 connection exists.

In either case, although the binding screw is ordinarily relied upon to hold the wire or cable, the armor or insulation fits within the enlarged passage so tightly that it is firmly 95 held and does not move around and bend at a short angle, as has been the case heretofore. Consequently, the danger of breaking the wire or cable just at the end of the insulation is entirely avoided and at the point 100 where the bending can occur it is so far distant from the end of the same that there is little danger of its breaking.

105 In Fig. 4 I have shown a modification in which the exposed end of the connection is devoid of indentations and exposed metal parts. This is simpler, has a better appearance, and does not present any danger of short circuiting the battery. In this case 110 the hard rubber plug is made in the same form as in the other figures, except that it has no openings in its larger end. The

binding screws 28 extend nearly all the way through the plug, from the small end and their heads act as the electrical contacts. They screw into conductors 27 and clamp 5 the ends of the cable in radial openings in their ends. It will be seen that these advantages are all secured at a minimum of expense and with a maximum of simplicity.

Although I have illustrated and described 10 only a single embodiment of the invention, I am aware of the fact that many modifications can be made therein by any person skilled in the art without departing from the scope of the invention as expressed in 15 the claims. Therefore I do not wish to be limited to all the details of construction herein shown and described, but

What I do claim is:—

1. As an article of manufacture, an electrical connector comprising a flat-ended cylindrical molded insulator constituting a plug and having radial pins for entering bayonet slots, a conductor embedded therein flush at one end with the end surface of 25 said plug and extending nearly but not quite to the other end, a binding screw extending longitudinally into one end of the conductor, the plug having a radial handle at the end provided with a perforation extending to the conductor for receiving an armor or insulation, said conductor having a passage for receiving a wire or cable in the armor or insulation, in position to be secured by said binding screw.

35 2. As an article of manufacture, an electrical connector comprising a flat-ended cy-

lindrical molded insulator constituting a plug, a conductor embedded therein and having its end substantially flush with the surface of the flat end of the plug and extending nearly but not quite to the other end, a binding screw extending longitudinally into said other end of the conductor, the plug having a flat radial handle at the end provided with a perforation extending 40 to the conductor for receiving an armor or insulation, said conductor having a passage for receiving a wire or cable in the armor or insulation in position to be secured by said binding screw.

3. As an article of manufacture, an electrical connector comprising a flat-ended cylindrical molded insulator constituting a plug, having two radial pins near one end to engage a bayonet socket, a pair of conductors embedded therein and having their ends substantially flush with the surface of the flat end of the plug and extending nearly but not quite to the other end, two binding screws extending longitudinally into said 60 other end of the conductor, the plug being countersunk to receive the heads of the screws and having a flat radial handle at the countersunk end provided with two perforations extending to the conductors for receiving an armor or insulation, said conductors having passages for receiving a wire or cable in the armor or insulation in position to be secured by said binding screws.

In testimony whereof I have hereunto set 70 my hand.

JASON C. STEARNS.
